DETACHABLE LOOP FASTENER FOR
GARMENTSWilliam A. Mysels and Robert Isenberg,
Chicago, Ill.

Application June 28, 1937, Serial No. 150,688

4 Claims. (Cl. 2—96)

This invention relates generally to fastening means employed with fur coats and the like, and more particularly, to a detachable and removable means of this character.

It is well known that in the manufacture of fur coats the same are provided with loops by means of which the coat is fastened on the person. These loops become worn, however, after a short time in use, and it becomes necessary to replace them. To do so with coats of present manufacture is rather difficult and expensive and it is, therefore, the main object of this invention to provide a detachable loop fastener whereby the same may be readily and quickly replaced whenever it becomes necessary or desirable to do so.

Another object of the invention is to provide detachable fastening means for fur coats and the like, comprising a pair of hooked members normally secured to the inner lining of the coat and to which the free ends of a loop may be detachably secured, said hooked members being normally concealed from view when the loop is in assembled operative position on the coat.

A further object of this invention is to provide a loop fastener of the character described for use on fur coats and the like, said loop being adapted for detachable engagement in operative position with a pair of members permanently secured to the coat body, said last mentioned members being normally concealed from view, but being capable of movement to exposed position to facilitate the attaching of the ends of the loop thereto.

A still further object of the invention is to provide a device of the character described which will be simple in construction and assembly, which may be produced along lines convenient for low cost manufacture and which will at the same time be highly efficient for carrying out the purposes for which it is designed.

With the foregoing and other objects in view, which will appear as the description proceeds, the invention consists in certain novel features in construction, arrangement and combination of parts herein more fully described, illustrated in the accompanying drawing and particularly pointed out in the appended claims, it being understood that various changes in the form, proportion, size, and minor details of the structure may be made without departing from the spirit or sacrificing any of the advantages of the invention.

For the purpose of facilitating an understanding of our invention, we have illustrated in the

accompanying drawing a preferred embodiment thereof, from an inspection of which, when considered in connection with the following description, our invention, its mode of construction, assembly and operation, and many of its advantages should be readily understood and appreciated.

Referring to the drawing in which the same characters of reference are employed to indicate corresponding or similar parts throughout the several figures of the drawing:

Fig. 1 is a front elevational view of a garment provided with loop fasteners constructed in accordance with our invention;

Fig. 2 is a sectional view through a portion of said garment showing our detachable loop fasteners in operative position on said garment;

Fig. 3 is a view in perspective showing our loop fastener in the process of being connected to the garment; and

Fig. 4 is a view similar to Fig. 3 with the body of the garment removed.

Referring to the drawing more specifically by characters of reference, the letter A designates a garment such as a fur coat or the like, which garment is provided with buttons 10 and the loop members 11 by means of which said garment may be securely fastened on the person.

In the embodiment illustrated, the said loop members 11 may be constructed of any suitable material and are provided adjacent their free ends with suitable eyelets 12, by means of which the ends of said loop members are detachably secured to hook members 13, which hook members may be formed of any suitable material such as metal or the like.

As already stated, the main object of this construction is to enable to replace the loop members 11 whenever the same may become worn and it is necessary or desirable to do so with a minimum of labor and cost. The hook members 13 may be formed integral with a tubular body 14 which may be split along its bottom edge as shown at 15 and between which split portions may be securely clamped one end of a piece of elastic material 16, the other end of which may be securely fastened to the inner lining 17 of the garment by means of a row of stitching 18 or in some other suitable and well known manner. Provided directly adjacent each of said hook members 13 in said body A of the garment is a slit 19 through which said members 13 may extend as shown more clearly in Fig. 3, whenever it is desired to pull said hook members through said slits for the purpose of attaching thereto the

free ends of the loop member 11. The elasticity of the strips 16, it will be noted, will permit said members to be pulled out through said slits 19 but to hold the same concealed from view 5 when the loop members are in fully assembled operative position on the garment. It will also be noted that the said flexible strips 16 are of such a size and possess such elasticity as to normally remain concealed from view and to afford a secure fastening means when the coat 10 is worn in a fastened condition but to readily permit the withdrawal of said hook members through the slits 19 when it is desired to replace the loop member 11.

15 Obviously there are many ways in which the said hook members 13 may be permanently and securely fastened to the inner lining of the garment and it is understood that we do not limit ourselves to the specifications means illustrated 20 in the drawing. The operation and result attained will be the same regardless of the specification means employed for securing the hook members within the garment so long as these members will normally remain concealed from 25 view but will readily permit their withdrawal through the slits 19 when it becomes necessary or desirable to replace the loop members 11. It will also be noted that the slits 19 are of such a shape and size as to be completely unnoticeable 30 when the garment is being worn, thereby not detracting from the normal appearance of the garment.

From the above, it will be apparent that we have provided a very simple and inexpensive 35 method for readily replacing the loop fasteners, which fasteners may be made up and kept in stock for replacement. The construction disclosed is such as to permit the replacement of the loop members by unskilled persons in a minimum of time and with no cost for labor and the like.

It is believed that our invention, its mode of construction and assembly, and many of its advantages should be readily understood from the 45 foregoing without further description, and it should also be manifest that an embodiment of the invention has been shown and described for illustrative purposes, the structural details are nevertheless capable of wide variation within the 50 purview of our invention as designed in the appended claims.

What we claim and desire to secure by Letters Patent of the United States is:

1. In combination with a garment, of means 55 for fastening said garment on the person, said means including a pair of members permanently

secured to the inner lining of said garment and normally concealed from view, a loop member having its free ends in detachable engagement with said first mentioned members, and means for permitting the withdrawal of said first mentioned members for the purpose of attaching said free ends of said loop member thereto. 5

2. In combination with a garment, of means for fastening the same on the person, said means including the strip of material, the free ends of 10 which are extended through slits provided in the body of the garment for detachable engagement with a portion of the inner lining of the garment, said detachable engagement being accomplished by hook members yieldingly connected to said inner lining, the yielding connection being such as to normally retain said hook members concealed from view but to permit their withdrawal for facilitating the attaching of free ends of said strip thereto. 15

3. In combination with a garment, of means for fastening the same on the person, said means including a pair of hook members permanently secured by means of flexible strips to the inner lining of the garment and to normally remain concealed from view when the garment is being worn, a loop member having its free ends detachably secured to said hook members, said free ends extending through slits provided in the body of the garment and remaining concealed from 20 view in their normal operative position, said hook members being capable of withdrawal through said slits to facilitate the detachable engagement of said free ends therewith. 25

4. In combination with a garment, of means for fastening the same on the person, said means including a pair of hook members and a pair of flexible strips, one end of each of said strips being permanently secured to the inner lining of the garment and the other end of which is secured to 35 one of said hook members, a loop member adapted for having each of its free ends detachably connected to one of said hook members, said free ends extending through slits provided in the body of the garment and being retained by said 40 hook members in normally concealed position when said loop member is in operative engagement with said hook members, said flexible strips being adapted for normally retaining said hook members concealed from view but permitting the 45 withdrawal of said hook members through said slits to facilitate the connection of the free ends of said loop member to said hook members. 50
